UNITED STATES PATENT OFFICE.

HENRY C. HUTCHINSON, OF KINGMAN, KANSAS.

WIND-WHEEL.

SPECIFICATION forming part of Letters Patent No. 357,282, dated February 8, 1887.

Application filed October 25, 1886. Serial No. 217,144. (No model.)

To all whom it may concern:

Be it known that I, HENRY C. HUTCHINSON, a citizen of the United States, residing at Kingman, in the county of Kingman and State of Kansas, have invented certain new and useful Improvements in Wind-Wheels; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention has relation to wind-wheels of that class known as "horizontal wind-wheels;" and its object is to provide mechanism by which the shaft may be driven in any desired direction without regard to the direction in which the wind may be blowing.

To this end the novelty consists in certain novel features, hereinafter described, and specifically pointed out in the claims.

In the drawings, Figure 1 is a side elevation, 25 Fig. 2 is a vertical central section, and Fig. 3 is a plan view, of a wind-wheel provided with my improvements.

Referring to the drawings by letter, A indicates the posts, and A' the cross-beams, of 30 the supporting frame or tower, which may be of any desired size or material. Near the corners of the tower I provide the braces *a*, which are secured to the meeting cross-beams, as shown most clearly in Fig. 3. The vertical 35 valves or windows B are journaled between the upper and lower cross-beams, A', and the upper and lower corner-braces, *a*, by means of the pivot-pins *o*. They are connected one with another, so as to be operated simultaneously, by means of the rods *b*, which extend around the entire series of valves and engage lips B², extending from projections B' on each valve.

C is the wind-wheel shaft, and C' the vanes 45 which radiate therefrom and are rigidly secured thereto. The shaft C is surrounded above and below the vanes by tubes D, the lower one resting upon beams *d*, secured to the diagonally-opposite posts of the tower and 50 intersecting at their centers. The upper tube, D, is secured to and depends from two similar

diagonal beams, *d'*, secured to the upper ends of the posts A.

Above and below the vanes C', I provide a series of horizontal valves or windows, E, which are journaled in the tubes D and in the beams A' and braces *a*, by means of pivot-pins *r*. 55 These horizontal valves or windows are provided with projections *e*, and are all connected by rods E', which engage these projections in order that the valves may be operated simultaneously.

A rotating post, F, is supported at one side of the tower by and between two beams, F', which are secured upon the diagonal beams *d* and *d'*, and extend past the tower, as clearly shown. 65 The rotating post F has cross-trees G secured to it near its upper and lower ends, as shown, and these cross-trees are connected with the valves or windows by means of rods *g*, and thereby serve to open and close the same in the operation of the device. The lower cross-tree, G, is connected with the lower series of horizontal valves or windows, and the upper cross-tree is connected with the series of vertical valves and the upper series of horizontal valves. 70 The lower cross-tree is also connected by means of rods *h* to the ends of the longer arms of a pair of bent levers H, which are secured to a shaft, H', journaled in the posts A, and passing through the angle of the bent levers. 75 The ends of the shorter arms of the bent levers are connected by rods or links *i* to a lever, I, which is pivoted to a suitable support, I', and is provided with a lug which engages the notches in a curved rack-bar, J, also secured to support I'. The pivot of the lever I is between the angle-levers H, and the opposite ends of the cross-trees are consequently moved in opposite directions when the lever I 80 is operated, as will be readily understood.

The operation of my device is simple, and will be readily appreciated. When the lever I is at the central notch of the rack J, as shown in the drawings, the valves will all be 85 closed, and the wheel will consequently be at rest. By raising or lowering the lever I the valves will be opened and turned so as to deflect the wing to either the right or left side of the vanes, and consequently turn the shaft in 90 whichever direction it may be desired to drive it.

Having thus described my invention, what I claim, and desire to secure by Letters Patent, is—

1. The combination, with the wind-wheel, of a series of vertical windows, a series of horizontal windows above and below the vertical windows, and mechanism, substantially as described, for simultaneously operating all the windows.
- 10 2. The combination, with the wind-wheel, of the vertical and horizontal windows, a rotatable post to one side of the wind-wheel

provided with cross-trees, rods connecting the cross-trees with the windows, and mechanism, substantially as described, for rotating the 15 post and cross-trees whereby the windows are operated.

In testimony whereof I affix my signature in presence of two witnesses.

HENRY C. HUTCHINSON.
